UNITED STATES PATENT OFFICE.

MARIE OLPE, OF JAMAICA, NEW YORK.

WASHBOARD REST.

Application filed January 19, 1925. Serial No. 3,513.

To all whom it may concern:

Be it known that MARIE OLPE, a citizen of the United States of America, residing at Jamaica, in the county of Queens and State 5 of New York, has invented new and useful Improvements in Washboard Rests, of which the following is a specification.

The object of the invention is to provide a device for use in connection with wash- 10 tubs to support the remote or lower end of the washboard above the plane of the bottom of the tub, so that the operator, in use, may stand in a position more nearly approach- 15 ing an upright position and thus be relieved of the back strain ordinarily attend- 20 ing the use of a washboard; to provide a device which may be readily attached to the tub; and to provide for adjustment so that the operator may effect the most convenient positioning of the washboard.

With this object in view, the invention consists in the construction and combination of parts of which a preferred embodiment is illustrated in the accompanying drawings, 25 wherein:

Figure 1 is a view showing the invention applied in operative position, the washtub being shown in section.

Figure 2 is a vertical sectional view on the plane indicated by the line 2—2 of Figure 1.

Figure 3 is a detail sectional view on the plane indicated by the line 3—3 of Figure 2.

Figure 4 is a detail sectional view on the plane indicated by the line 4—4 of Figure 2.

The device consists of a pair of brackets 1 made preferably of strap metal but stout enough, however, to give them stability. The brackets at their upper ends are formed with return bends constituting hooks 2 by which the brackets may be supported on the tub 3 by engaging the hooks with the upper edge of the rear wall of the tub.

While the upper portions of the brackets 45 are flat, the lower portions are formed to provide channel members 4 with connected lateral flanges 5 constituting bearing feet engaging the inner face of the back wall of

the tub. In the web portions of the channels 4, keyhole slots 6 are formed, one above 50 the other, for engagement with the headed studs 7 carried by a transverse rest 8. By means of the keyhole slots, the position of the rest 8 with reference to the upper edge of the tub may be varied, depending on the 55 slots 6 engaged by the studs 7.

The rest 8 is transversely angular and is provided with an upturned longitudinal lip 9 extending the full length thereof, a series of drain openings 10 being provided to permit the water which reaches the rest to flow back into the tub. The foot of the wash- 60 board 11 is carried by the rest 8 and by the proper adjustment of the latter, the board may be positioned as desired, the lip 9 tend- 65 ing to retain it in position on the rest during the backward stroke of the hands in the scrubbing operation.

By forming the brackets with the channels 4, clearance space for the heads of the 70 studs 7 is provided.

The invention having been described, what is claimed as new and useful is:

1. A device for the purpose indicated comprising a plurality of brackets for sus- 75 pension within a washtub, and a rest spanning the brackets and adapted to receive the foot of a washboard to elevate the foot or remote portion of the washboard above the plane of the bottom of a tub, the rest being 80 provided with a longitudinal upturned lip to retain the foot of a washboard thereon during the back stroke in the operation of scrubbing.

2. A device for the purpose indicated comprising a bracket for engagement with the wall of a washtub for suspension within the same, and a rest for supporting the foot of a washboard, said rest being carried by the bracket and provided with an upturned lip 90 to retain the foot of a washboard thereon and with drain openings for the passage of water trapped thereon.

In testimony whereof she affixes her signature.

MARIE OLPE.
